UNITED STATES PATENT OFFICE

160,131

TELEVISION RECEIVER

Carl J. Steinke, Chicago, Ill., assignor to Zenith
Radio Corporation, a corporation of Illinois

Application October 13, 1948, Serial No. 149,103

Term of patent 7 years

(Cl. D56—4)

To all whom it may concern:

Be it known that Carl J. Steinke, a citizen of the United States, residing at Chicago, in the county of Cook and State of Illinois, has invented a new, original, and ornamental Design for a Television Receiver, of which the following is a specification, reference being made to the accompanying drawings, forming a part thereof.

In the accompanying drawings, Fig. 1 is a perspective view of the front, top and side of a television receiver showing my new design; Figure 2 shows a front elevation of the receiver, and Figure 3 shows a side elevation of the receiver. The characteristic features of the design reside in the front panel section.

I claim:

The ornamental design for a television receiver, substantially as shown and described.

CARL J. STEINKE.
